UNITED STATES PATENT OFFICE.

MARION F. McCORMICK, OF GRIFFITH, INDIANA.

SOUND BOX FOR TALKING MACHINES.

Application filed October 28, 1920, Serial No. 420,164. Renewed January 10, 1924.

To all whom it may concern:

Be it known that I, MARION F. McCORMICK, a citizen of the United States, residing at Griffith, in the county of Lake and

5 State of Indiana, have invented new and useful Improvements in Sound Boxes for Talking Machines, of which the following is a specification.

This invention relates to certain new and 10 useful improvements in a sound box for talking machines and has for its purpose to provide an improved construction to eliminate the scratching noise or sound which accompanies the playing of a record.

15 It is well known that the needle, in reproducing a record, causes a scratching or grating sound as the record is moved thereby, which sound often renders the reproduced notes indistinct and is caused by friction 20 through the dragging of the rotating record or disk beneath the needle, the latter being fixed relative to the sound box. The primary aim of this invention is to mount the playing needle on the sound box so as to 25 move in rolling contact with the record and not drag over the same.

The further object resides in a needle 30 journaled on the sound box so as to rotate on its longitudinal axis and thus have a 35 rolling contact with the record to thereby prevent the needle being dragged over the latter.

The invention has for a further object to provide a rotatable needle combined with 40 needle rotating means which is operated by the record rotations.

The invention further resides in the features of construction and the arrangements and combinations of parts described in detail in the following specification and defined in a succinct manner in the appended claims, reference being had to the accompanying drawings wherein.

Figure 1 is a front elevation of the improved invention;

Figure 2 is a transverse vertical section thereof on line 2—2 of Figure 1,

Figure 3 is a horizontal section thereof depicting the mounting of the needle;

50 Figure 4 is a horizontal section on line 4—4 of Figure 3;

Figure 5 is a partial elevation disclosing a modified mounting of the needle in which the needle has no positive drive;

55 Figure 6 is a fragmentary front elevation

of the sound box further disclosing the modified construction; and

Figure 7 is a section on line 7—7 of Figure 6;

Figures 8 and 9 are horizontal sectional views illustrating further modified needle mountings and rotating drives;

Figures 10 and 11 are plan views of blanks from which the stylus rods disclosed in Figures 8 and 9, may be made from sheet steel or other metal; and

Figure 12 is a fragmentary sectional view showing diagrammatically a sound record and a stylus in playing position thereon.

Referring more in detail to the drawings, 70 1 designates the body or casing of the sound box having a vibratory diaphragm 2 secured to the casing, as by screws 3 and ring 4.

The stylus rod 5 has its upper end centrally fixed to the diaphragm and its intermediate portion equipped with oppositely extending trunnions 6 that are journaled on the bearing points 7 screw threaded through upstanding lugs 8 on the clamping ring 4. 80 The lower end of the stylus rod is provided with a stylus bearing 9 and a thrust bearing 10, the latter being connected to the former by the integral frame or arm 11. A laterally disposed oil cup 12 communicates 85 with the bearing 9 and a lubricant cup 13 is formed in the bearing 10, said oil cups being packed with an oil absorbent material as illustrated.

An L-shaped bracket or support 14 is 90 secured to body 1 and extends forwardly to provide a resilient or yieldable arm on the outer end of which is mounted a journal box 15, and in this bearing is journaled a shaft 16 carrying a wheel or pulley 95 17. The shaft bearing is formed with an oil duct or chamber 18 packed, as indicated, to hold a supply of the lubricant therein.

The stylus 19 is journaled in the bearings 9 and 10, the inner end being pointed and 100 engaging in the thrust bearing 10 while the outer or playing end of the stylus is spheroidal or ball-shaped, the ball point 20 being adapted to roll in the record grooves. A flexible, resilient belt 21 is passed about the pulley and that portion of the stylus between the bearings 9 and 10 for imparting rotation to the ball point as it traces the sound or record grooves. The belt, in its travel beneath the pulley frictionally 105 110

engages the sound record and provides a track-laying drive for the rotating stylus.

The pulley and diameter of the stylus at the point about which the belt passes, which portion can be considered as a driven pulley while the larger pulley can be termed the driving pulley, are proportioned to rotate the ball end of the stylus equal to the speed of the under-running record to thereby obviate all scratch and drag of the needle or stylus over the record. The resilient support for the drive pulley readily yields with the latter to accommodate for any irregular motion of the turntable.

In Figures 5, 6 and 7 the modified construction eliminates the needle drive and substitutes a novel mount for the stylus which consists of a bushing 22 inserted through the bearing 10' and threaded in the bearing 9', said bushing having a central lubricant chamber 23 extending axially through the rear end and closed thereat by a cupped plug 24 designated to act as a thrust bearing for the inner pointed end of the stylus 25. The forward end of the stylus is journaled in the bushing, as at 26 and has its protruding extremity in the shape of a ball 27 for rolling in the sound groove. The chamber 23 is intended to contain a lubricant-absorbing filler.

In Figure 8, I provide the stylus 28 with a shoulder 29 on its inner end which cooperates with an internal shoulder 30 in the bushing or barrel 31 for preventing longitudinal displacement of the stylus, the latter having a peripheral groove immediately adjacent its balled point in which a round belt 32 engages, as driven by the drive pulley 33.

Figure 9 discloses a flat belt drive 34 for a stylus 35 which is journaled at each end portion in box bearings 36, said bearings being formed by bending the terminal portions of the blank disclosed in Figure 11 into rectangular shape to not only journal the stylus but also to serve as holders for the lubricant-absorbent material, as shown.

The diagrammatic illustration in Figure 12 clearly indicates the manner in which the greater portion of the ball point rolls on the outer wall of the record groove to accommodate the greater distance about the disk, the inclination of the stylus permitting the ball point to have excellent contact in the groove.

In either form the ball pointed stylus or needle has rolling contact in the record groove for eliminating any dragging or scratching sound. The stylus is inclined slightly with respect to the record and accordingly the stylus-supporting bearings on the lower ends of the stylus rods 5 are also inclined. Furthermore, as depicted in Figure 5, it will be observed that the stylus on its inward travel across the record main-

tains a constant radial disposition for the better rolling of the ball point.

Obviously, various changes in form and construction can be resorted to as may fall within the scope of the appended claims 70 without departing from the spirit of my invention.

The term "needle" as herein employed, and especially in the claims, comprehends any stylus or device or the like which engages the record for the purpose of reproducing the sound.

What is claimed is:

1. In combination with a reproducible record, a sound box, a casing, a diaphragm therefor, a stylus rod connected to the diaphragm and formed with a stylus bearing, a stylus journaled in said bearing transversely of the record groove, a wheel, a yieldable support therefor carried by the case and a driving belt engaging the record and passing about the wheel and the stylus for rotating the latter.

2. In a sound box, a stylus rod having a journal bearing intermediate its ends and a thrust bearing at its inner end, and means intermediate the bearings for rotating the rod.

3. In combination with a reproducible record, a sound box, a needle mounted to have rolling contact with the record in the direction of rotation thereof, and means proportioned to rotate the needle at the point of contact with the record at a speed to give the reproducing point a circumferential velocity equal to the speed of travel of the record there beneath whereby said needle will have a non-rub rolling contact with said record.

4. In combination with a reproducible record, a sound box, a needle rotatably supported transversely of the record groove for having a rolling contact therewith, and means for rotating the needle in the direction of rotation of the record and commensurate with the speed thereof to eliminate dragging of the needle when reproducing sound.

5. In combination with a reproducible record, a sound box, a needle rotatably supported substantially radially of the playing record for having a rolling contact on the side therewith, and means for rotating the needle in the direction of rotation of the record commensurate with the speed thereof 120 to eliminate dragging of the needle thereover.

6. In combination with a sound record and the sound box of a talking machine, a needle rotatable on its longitudinal axis transversely of the sound record, and means proportioned to rotate the needle at a speed to give the playing point a circumferential velocity equal to the speed of travel of the playing disk beneath the needle whereby 130

said playing point will have a rolling contact with the disk.

7. In combination with a reproducible record, a sound box for talking machines, a body, a diaphragm, a stylus rod mounted on the body and attached to the diaphragm, and a stylus rotatably mounted in the outer end of the rod and disposed pointing inwardly and radially throughout its bodily movement over the record.

8. In combination with a reproducible record, a sound box for talking machines, a body, a diaphragm, a stylus rod mounted on the body and attached to the diaphragm, the outer end of the rod provided with spaced stylus bearings, a stylus mounted therein, a drive wheel carried by the body, and a belt engageable with the record and passing about the wheel and the stylus for rotating the stylus.

9. In combination with the record of a sound reproducing machine, a stylus and means for rotatably supporting the stylus at an incline to the record and transversely

of the sound groove of the record to have 25 rolling contact therewith.

10. In combination with the record of a sound reproducing machine, a stylus, means for rotatably supporting the stylus transversely of the sound groove of the record to 30 have rolling contact therewith, and track-laying driving means for the stylus.

11. In combination with the record of a sound reproducing machine, a stylus having a spheroidal point, and means rotatably supporting the stylus for rolling contact of the spheroidal point on the record.

12. In combination, a record, and a rotatable, ball-pointed, sound reproducing needle supported and inclined with respect 40 to the record, transversely of the reproducing portion of said record, so as to have a rolling contact therewith in reproducing sound, and means for positively rotating the needle.

In testimony whereof I have hereunto set my hand.

MARION F. McCORMICK.
